JOHN W. HOOSER, OF DALLAS, TEXAS.

CARBURETING SYSTEM FOR INTERNAL-COMBUSTION ENGINES.

1,217,448.

Specification of Letters Patent. Patented Feb. 27, 1917.

Application filed January 16, 1917. Serial No. 142,678.

To all whom it may concern:

Be it known that I, JOHN W. HOOSER, a citizen and resident of Dallas, county of Dallas, State of Texas, and United States 5 of America, have invented certain new and useful Improvements in Carbureting Systems for Internal-Combustion Engines.

This invention relates to a new and useful 10 form of carbureter adaptable for use on internal combustion motors and is conceived and designed for vaporizing fuel oils of the heavier and non-volatile class for combustion in the engine.

A further purpose of the invention is to 15 provide a carbureting system for automobile engines which will produce a resulting gas of such a quality as will give perfect combustion.

The carbureting device constituting this 20 invention, an example of which is disclosed in this Letters Patent, particularly appertains to a thermal carbureting system for vaporizing, through the agency of heat from the running motor, oils of low specific gravity 25 such as that grade of oil which is known and sold in the market as coal oil. The thermal carbureter included in this invention provides means for mixing with the coal oil vapor a light steam vapor, which water vapor or steam is passed to and thoroughly 30 intermixed with a combustible vaporized mixture prior to combustion in the cylinder of the engine. This provision of the vapor used in connection with the hydrocarbon oil 35 vapor softens and tones down the combustible mixture to a degree which is most efficient and thoroughly combustible in explosion chamber at the point of highest compression, for the reason that the explosive 40 mixture combined with the humid water vapor cuts and disintegrates the carbon which would otherwise form at the point of combustion within the cylinder and cause the explosion chamber and all parts associated therewith, including the spark plug 45 of the engine, to be thoroughly cleaned and scoured at the point of pressure of the power impulse delivered by the comparatively quick and cleansing explosion of the said 50 mixture.

With the above and other objects in view the invention has relation to a certain combination and arrangement of parts, an example of which is described in the following 55 specification pointed out in the appended

claims, and illustrated in the accompanying drawings; wherein,

Figure 1 is a view of the carbureting system in its entirety shown in side elevation with many parts in section and which device 60 is shown in position on a diagrammatical form of gas engine or automobile motor.

Fig. 2 is a cross sectional view taken through one of the manifolds included in the invention and shows in form the general 65 shape and construction of said manifold.

Referring now more in particular to the drawings, wherein the same parts are designated by the same reference characters throughout the views, the numerals 1 and 70 2 point out a certain form of duplex generating manifold. This form of generating manifold comprises an exterior substantially large exhaust duct 1 which is provided with the usual exhaust receiving ports 3 opening 75 directly into the said manifold and connecting with the exhaust ports leading from the cylinder of the engine. The manifold will preferably be formed tapering in design, enlarging from one end to the other as the 80 volume of heated gases entering the manifold increase, that they may be readily passed, without back pressure, from the motor cylinders. The internal manifold 2 is preferably formed and cast integrally 85 with the part 1, and is provided with connecting flanges 4, or any suitable means for effecting connection with other parts. The internal manifold 2 may be formed with a tapering design similar to the exhaust manifold, and is arranged in the central portions of said exhaust manifold. The usual form of intake manifold or duct 5 is provided with ports 6 for connecting with the intake 90 ports of the cylinders. A connecting tube 95 7 is employed to connect the generating manifold with the intake manifold 5 and is of sufficient size to adequately carry the gases from the manifold 2 to the engine. The usual form of carbureter 8 may be employed 100 and is connected to one extremity of the internal manifold 2 and is provided with fuel supply pipe 9 which furnishes the carbureter with a constant flow of coal oil or other fuel to be used. An air intake valve 10 equipped with a dash regulating means 11 is connected with the manifold 7 or at a point in the ducts after carburization has 105 been effected. This air intake valve is employed for the purpose of admitting air to 110

the vaporized mixture in quantities governed by the driver of the car engaged from the dash by the device 11, means being provided for varying of the pressure by the 5 usual form of spring pressed intake valve thereby governing the flow of the volume of air into the volatilized mixture. A steam dome of comparatively small size and comprising a cylindrical shell 12 is openly connected with the water radiating system of the engine at any convenient point thereof where such connection may be had to best obtain a small quantity of the water vapor or steam which forms around the cylinder 10 heads during the high temperature of operation of the engine. A tube 13 is provided with a regulating valve 14, and connects with the vapor dome 12 and leads a regulated quantity of steam from the water jacket to any point centrally located in the 15 intake manifold 5. A small pipe or tube may be directly connected with the water jacket without employing the use of the steam dome, but same is herewith employed to furnish a ready supply of collected steam 20 to the tube. The numeral 15 points out a portion of the water jacket or cooling system of the engine where the same may be conveniently tapped, and the connection made therefrom to the intake manifold. A hand regulating device 16 provided with a connecting rod 17, which rod is connected through a flexible joint to the valve 14, is conveniently accessible from the dash to the 25 operator of the car for gaging the quantity of vapor admitted to the explosive mixture.

The vaporization of the kerosene oil is found to be so thorough in its vaporized quality as to give, after having the proper 30 amount of air mixed with such vapor gas, a blue flame of a perfect hue, indicating through actual experiments that the gas generated by this system is of a quality and nature very perfect and properly vaporized 35 for most efficient combustion.

In carbureting systems where heat is relied upon for the generation of the fuel it is sometimes desirable to provide convenient and quick priming methods for starting the 40 car giving the engine its initial high working temperature prior to using the non-volatile oil as fuel. With this in view the fuel tank 18 of small capacity is placed at any convenient point on the car such as the dash 45 where occasional filling can be had and has connection with the intake manifold of the system through a priming tube 19, which tube is provided with a cut off valve 20. The tube 19 is fixed within the intake manifold 50 and may be provided with apertures 21 for admitting the priming oil in the intake duct. In starting the motor equipped with this 55 form of thermal carbureting system, where the high degree volatile priming fuel is used for quick starting, valve 20 will be opened

for an instant only admitting a few drops or a very small quantity of the priming oil into the intake manifold and immediately cut off. The engine will readily start upon the original mixture administered to the intake which starting of the engine emits the exhaust gases from the exhaust ports into the manifold 1 heating up the carbureting manifold 2. The suction of the motor piston sets up a certain circulation of the fuel oil to be carbureted through the several manifold tubes, passing the said oil in contact with the hot walls of the carbureting manifold fuel instantly vaporizing it into gas, said gas being further raised in temperature as it passes through the manifold 2 and to the intake of the engine. The mixture of air and water vapor through the vaporized oil is best regulated by varying the water vapor flow and air supply to the mixture to suit the varying working conditions 85 of the engine.

The invention is presented to include all such changes and modifications as may come within the purview of the following claims: 90

Claims:

1. In a thermal carbureting device for internal combustion motors, the combination of an exhaust manifold comprising a substantially long tube of tapering design increasing in size from one extremity to the other, of a carbureting manifold carried in and arranged longitudinally within the said exhaust manifold, said carbureting manifold tapering from a substantially small sized tube to a larger sized tube to best accommodate the increasingly expanding gases, connection had with the intake manifold of the motor, and means employed to supply the carbureting manifold with fuel oil. 100
2. In a carbureting system for automobile engines, a manifold for conducting the intake and exhaust gases to and from the engine comprising a duplex form of manifold, which manifold consists of a tube or duct extending longitudinally through its companion tube or duct, the inner tube connecting with a fuel supply and connecting with the engine intake, and the duplex manifold increasing in size in cross section from end to 110 end. 115
3. In a thermal carbureting device for internal combustion motors, the combination of an exhaust manifold comprising a substantially long tube of tapering design increasing in size from one extremity to the other, of a carbureting manifold carried in and arranged longitudinally within the said exhaust manifold, said carbureting manifold tapering from a substantially small sized tube to a larger sized tube to best accommodate the increasingly expanding gases, connection had with the intake manifold of the motor, and means employed to supply the carbureting manifold with fuel oil, and an 120
- 125
- 130

air intake valve located in the carbureting manifold.

4. A method of producing combustible mixture from kerosene, consisting of the following steps: first, mixing kerosene and air; second, vaporizing said kerosene by heat; third, mixing air therewith; and, finally, injecting steam therewith.

5. In an internal combustion engine a carburetor for mixing kerosene and air, a heater through which the mixture of kerosene and

air passes, an auxiliary air inlet valve between the heater and engine, and means for introducing steam between the auxiliary air inlet valve and the engine.
